AUTOMATIC CLOCK SETTING MECHANISM

Joseph Brodie Smith, Manchester, N. H.

Application May 13, 1930, Serial No. 452,112

3 Claims. (Cl. 177—353)

This invention relates to setting or correcting mechanism for clocks and it is especially concerned with setting mechanisms designed to utilize the radio time signals which are broadcast by the United States Government daily.

It is the chief object of the invention to devise an apparatus which will automatically reset a clock or series of clocks in accordance with these signals and which will be simple in organization, reliable in operation, and economical to manufacture.

The nature of the invention will be readily understood from the following description when read in connection with the accompanying drawings, and the novel features will be particularly pointed out in the appended claims.

In the drawings,

Figure 1 is a diagrammatic view of an apparatus embodying this invention;

20 Figs. 2 and 3 are sectional and end views, respectively, showing certain details of the controller used in the apparatus shown in Fig. 1, together with means for operating the controller; and

25 Figs. 4, 5 and 6 are elevations showing successive operations performed by one of the units of the mechanism shown in Fig. 1.

Referring first to Fig. 1, the organization there shown comprises a radio receiving set 2 adapted to receive the radio time signals and to convert said signals into impulses, or to transmit impulses corresponding to said signals. The time signals start at 11:55 A. M. The complete set of signals consists of "dots" sent out at one 30 second intervals for the five minute period immediately preceding 12 o'clock, noon, except that one dot is omitted in the middle of each minute, and the last five dots of each minute are omitted. Ten dots corresponding to the ten seconds immediately preceding the stroke of 12 noon, also are omitted; or, in other words, there is a ten second gap in the signals immediately prior to 12 o'clock, noon, and the final dot comes in at exactly 12 o'clock. As above indicated, 40 the radio receiver 2 is designed to transmit electrical impulses corresponding to the dots of the time signals. These impulses are sent from the receiver through a circuit 3 to a solenoid or electro-magnet 4. The armature 5 of this solenoid is pivoted at 6 on a bracket 1, and it is normally held in a raised position by a coiled spring 8, the movement of the armature under the influence of this spring being limited by a stop screw 10. Carried by, but insulated from, the 45 armature 5 is a movable contact 12 adapted

to engage a stationary but adjustable contact 13 to close the setting circuit through one or more clocks 14. In the arrangement shown these clocks are all connected in parallel in a circuit supplied with current from the battery 15. An impulse transmitted through the circuit 3 and solenoid 4 will tend to operate the armature 5 to close the switch 12—13 of the clock setting circuit 15. This movement, however, normally is prevented by a controlling apparatus or selector so organized that the switch 12—13 is allowed to close only upon the final dot of the time signals.

Normally the radio receiver 2 is inactive, and provision is made for turning it on or bringing it into operation at approximately the time that the signals start, namely, 11:55 A. M. For this purpose the battery circuit or filament circuit 16 of the receiver is arranged to include a normally open switch 17 which is under the control 20 of a clock mechanism. As shown in Fig. 1 the clock, which may be one of the clocks 14, or an independent clock, as desired, is equipped with a cam disk 18 so connected with the time mechanism that it makes one complete revolution every twenty-four hours. An arm 20 pivoted at 21 on the bracket 22 is provided with a finger 23 which bears against the edge of the cam disk 18 and with another finger 24 for engaging one of the spring supported contacts of the switch 17. A spring 25 tends to raise this arm and holds the finger 23 constantly against the cam 18. Formed in the edge of this cam is a notch 26 provided with a step 27. At approximately 11:55 A. M. the edge of this notch 26 slides over the end of the finger 23 and permits the spring 25 to move the arm 20 upwardly far enough to cause the finger 24 to close the switch 17, as shown in Fig. 4, thus closing the battery circuit or filament circuit of the radio receiver 2. At this time the upper end of the finger rests in the notch 27 and it remains in this notch for a brief interval, say two minutes, by the end of which time the disk 18 has moved far enough to permit the finger 23 to move upwardly still further until it strikes the bottom of the notch 26, as shown in Fig. 5. In this position of the arm 20 the finger 24 is raised far enough to close a second switch 28 of a circuit 30 leading to a motor 31, Fig. 1, which forms a part of the operating mechanism for the controlling apparatus, above referred to, for determining the precise point in the time signals at which the switch 12—13 will be closed.

Preferably this motor is of the small synchro-

nous type, such as those used in clocks, although it may be of any other suitable form capable of being controlled by the mechanism above described. Through reduction gearing indicated in Fig. 1 this motor drives a gear 32, Figs. 1, 2 and 3, fast on a spindle 33, and a controller is loosely mounted on this spindle, as best shown in Fig. 2, this controller consisting of a disk 34 secured fast on or integral with a sleeve 35 carrying a small pinion 36 at the end thereof opposite to the controller disk. Interposed between the disk 34 and the gear 32 is a dished or bowed spring 37, Fig. 2, which tends to press the disk 34 away from the gear, this movement, however, being limited by a collar 38 secured on the spindle 33. Due to this arrangement the controller disk 34 tends to revolve with the gear 32 but it can also be rotated independently of the gear.

20 The controller 34 carries two pins 40 and 41 insulated therefrom, and both designed to engage at certain times with a stop lever 42, Fig. 1. Normally the controller is held in the position shown in Fig. 1 by means of a sector 43, pivoted at 44, 25 and connected by a link 45 with an arm 46 which forms part of, or carries, an armature for the solenoid 41. This arm is pivoted at 48 and it is normally drawn away from the solenoid by a weak coiled spring 50.

30 Assuming that the cam disk 18 has been moved far enough to turn on the receiver 2 and to start the motor 31, it will be clear that the motor will operate through its connections with the controller disk 34 to revolve the controller slowly in 35 a counter-clockwise direction, as indicated by the arrow in Fig. 1. As each signal dot is transmitted through the receiver 2 and the electro-magnet 4, the armature 5 is drawn downwardly but is not allowed to close the switch 12-13 because the 40 spring mounted contact 51, carried by the armature 5, strikes the edge of the controller disk 34. When this occurs current from the battery 52 is transmitted through the disk 34 and the solenoid 41, as will be evident from the circuit connections shown in Fig. 1 thus energizing the solenoid and causing it to transmit a quick 45 rotative movement to the disk 34 in a clockwise direction, this movement returning the disk to the position shown in Fig. 1. As soon as the impulse 50 due to the signal dot dies out, the gear 32 again picks up the controller disk 34 and rotates it in a counterclockwise direction, this movement being interrupted a second later by the arrival of another dot of the signal. These operations are 55 repeated for a length of time depending upon the particular point in the time signals at which the controlling apparatus was brought into operation.

60 As above stated, there is an interval of ten seconds immediately prior to 12 o'clock noon, in which no signal dots are sent, and during this ten second interval the motor 31 and its connections with the controller 34 move the controller far enough to bring the notch 52 in the edge of the controller disk into a position immediately 65 under the contact 51. This occurs at about the expiration of the eighth second, or, in other words, two seconds prior to twelve o'clock. It will be observed, however, that the longest gap in 70 the time signals prior to this ten second interval is an interval of five seconds, and that the spacing of the contact 51 from the edge of the notch 52 is sufficiently great to prevent the edge of this notch arriving in alignment with the contact during 75 this five second interval. In other words,

during all of this time the controller 34 has been held in such a position that the armature 5 could not move far enough to close the switch 12-13 of the clock setting circuit. The parts are, however, caused to come into a relationship permitting this action at approximately two seconds prior to 12 o'clock. Consequently, when the final dot of the signals is received at 12 o'clock and the armature 5 of the solenoid 4 is drawn downwardly, the contact 51 then enters the notch 52 10 and the armature is moved far enough to close the switch 12-13 of the setting circuit. Each of the clocks 14 is equipped with some suitable setting mechanism arranged to be operated by the closing of the circuit so that all of the clocks in 15 this circuit are simultaneously set to 12 o'clock, this setting action occurring substantially simultaneously with the final 12 o'clock dot of the time signals.

20 Provision is also made for restoring the controlling apparatus or selector to its initial condition and opening the switches 17 and 28 of the receiving set and motor 31, respectively, when the setting operation has been completed. For this purpose the pin 41 is so located on the controller disk 34 that it strikes the lever 42 immediately 25 after the switch 12-13 has been closed. This results in closing the switch 53, Fig. 1, which controls a circuit including electro-magnets or 30 solenoids 54 and 55, thus energizing both of these solenoids. The energizing of the solenoid 54 closes a mercury switch 56 which also closes the circuit through the solenoid 41, thus operating through the armature 46 of this solenoid and the sector 43 to return the controller disk 34 again 35 to the position shown in Fig. 1. When the solenoid 55 is energized it draws down the armature 20 to approximately the position shown in Fig. 6, where the end of the finger 23 is slightly below the lower edge of a guard 57 carried by the cam disk 18. This guard is pivoted on the disk 18 at 58 and the spring 59 normally acts on it to hold it yieldingly against a stop pin 60. It is moved away from this pin by its initial contact with the finger 23 when this finger drops into the notch 26, as shown in Figs. 4 and 5, but when it is lowered the guard 57 is swung over the upper end of the finger by the spring 59, so that when the switch 53 is opened an instant later by the return of the controller disk 34 to its original position and the solenoid 55 consequently is deenergized, the arm 23 then is held in its lowermost 45 position where the finger 24 cannot close either of the switches 17 or 28. Both of these switches normally are held open by the resiliency of the springs on which the spring contacts are mounted. Both the radio receiver 2 and the motor 31, therefore, are turned off substantially simultaneously 50 with the return of the controller 34 to its initial 55 position.

56 It will be clear, therefore, that when the solenoids 54 and 55 are energized the solenoid 55 will disconnect or turn off both the radio receiver 2 and the motor 31. The presence of the mercury switch 56 serves to delay for a small interval of time the energizing of the solenoid 41 which operates to return the controller 34 to its initial position. Consequently, such return of the controller does not occur until after the radio receiver 2 and the motor 31 are turned off, the return of the controller serving to deenergize all 60 three solenoids 54, 55 and 41.

65 It will now be appreciated that the invention provides a relatively simple organization which 70

operates entirely automatically to correct or set a clock, or series of clocks, when the time signals are broadcast. The apparatus is relatively inexpensive to manufacture and the various elements 5 of it are of such a nature that the entire organization has a high degree of reliability.

While I have herein shown and described a preferred embodiment of my invention, it will be understood that the invention may be embodied in 10 other forms without departing from the spirit or scope thereof. For example, the apparatus shown has been designed to utilize the particular set or series of time signals above described, but it is clear that it would operate equally as well 15 with some other time signals and that an apparatus of essentially the same organization could be used with a considerable variety of time signals to produce essentially the same results.

Having thus described my invention, what I 20 desire to claim as new is:

1. In a selector operative to close a circuit in response to an interval of predetermined minimum length occurring in the reception of a series of electrical impulses, the combination of 25 a switch for closing said circuit, said switch including a movable contact and another contact with which it cooperates, an electro-magnet operated by each of the impulses of the series, an armature for said magnet carrying said movable 30 contact and tending to cause its engagement with the other contact when the electro-magnet is energized, a rotatable controlling member having provision for preventing the engagement of the movable contact with the other contact in 35 certain positions of the member in response to the energization of the magnet and permitting such engagement in another position thereof, means including a motor connected to said controlling member for rotating it at a predetermined 40 rate in one direction from said certain positions to said other position, return means for rotating the controlling member in the opposite direction, a circuit including said return means, and circuit closing means for said last mentioned 45 circuit comprising a second contact carried by said armature and cooperating with said controlling member in said certain positions only, whereby during the reception of impulses the return means will be repeatedly operated to rotate 50 the controller in the direction opposite to its rotation by the motor but during the predetermined interval will permit the motor to move the controlling member to a position permitting the first mentioned switch to close its circuit in response 55 to the impulse following the interval.

2. In a selector operative to close a circuit in response to an interval of predetermined minimum length occurring in the reception of a series of electrical impulses, the combination of a 60 switch for closing said circuit, said switch including a movable contact and another contact with which it cooperates, an electro-magnet op-

erated by each of the impulses of the series, an armature for said magnet carrying said movable contact and tending to cause its engagement with the other contact when the electro-magnet is energized, a rotatable controlling member having provision for preventing the engagement of the movable contact with the other contact in certain positions of the member in response to the energization of the magnet and permitting such engagement in another position thereof, means including a constant speed motor connected to said controlling member for rotating it at a constant rate in one direction from said certain positions to said other position, return means for rotating the controlling member in the opposite direction, a circuit including said return means, circuit closing means for said last mentioned circuit comprising a second contact carried by said armature and cooperating with said controlling member in said certain positions only, whereby during the reception of impulses the return means will be repeatedly operated to rotate the controller in the direction opposite to its rotation by the motor but during the predetermined interval will permit the motor to move the controlling member to a position permitting the first mentioned switch to close its circuit in response to the impulse following the interval, further circuit closing means, means operated by the controlling member for closing 20 said further circuit closing means immediately after the closing of the first mentioned switch, and an additional circuit for said return means closed by said further circuit closing means.

3. In a selector operative to close a circuit in response to an interval of predetermined minimum length occurring in the reception of a series of electrical impulses, the combination of a switch for closing said circuit, a radio receiver for receiving signals and relaying electrical impulses corresponding to them, operating mechanism for said switch including apparatus arranged to be actuated by the latter impulses, a rotary controller cooperating with said switch to prevent said operating mechanism from closing it in certain positions of the controller but permitting closing movement of the switch in another position of the controller, an electric motor for rotating said controller toward the latter position, electro-magnetic means responsive to the last mentioned electrical impulses to rotate said controller in the opposite direction against the action of said motor, whereby said motor will move said controller into position for the closing of said switch during an interval of predetermined minimum length in the reception of said signals, electro-magnetic re-setting means for restoring the selector to its initial condition after said switch has been closed, and a circuit for said re-setting means under the control of said controller.

JOSEPH BRODIE SMITH.
